UNITED STATES PATENT OFFICE.

ELISHA MORGAN, OF SPRINGFIELD, MASSACHUSETTS.

PAPER-CUTTING MACHINE.

SPECIFICATION forming part of Letters Patent No. 398,341, dated February 19, 1889.

Application filed April 4, 1888. Serial No. 269,637. (No model.)

To all whom it may concern:

Be it known that I, ELISHA MORGAN, a citizen of the United States, residing at Springfield, in the county of Hampden and State of Massachusetts, have invented new and useful Improvements in Paper-Cutting Machines, of which the following is a specification.

This invention relates to paper-cutting machines or presses in which a heavy cutter-board is used, on which the paper is placed to be acted on by a cutter for cutting envelope-blanks and for other similar uses, the object being to improve the construction of the bed of the machine to the end that the manipulation of said cutter-board may be facilitated and rendered less fatiguing to the operator, and that the paper-cuttings or waste may be removed from the bed of the machine by the movement of the cutter-board thereon, in order that they may not interfere with the operating devices.

In the drawings forming part of this specification, Figure 1 is a side elevation, partly in section, of a paper-cutting machine having my improvements applied thereto, the legs of the machine being shown broken off. Fig. 2 is a plan view of the bed and adjoining table of the machine and of the cutter-board. Fig. 3 is a vertical section of a portion of the bed of the machine, in which are shown in side elevation and section one of the spring-supported rolls and its supporting devices, all of which are hereinafter fully described. The parts of Fig. 2 shown in section are taken about on line *x x*, Fig. 1.

In the drawings, *A* indicates a portion of the supporting-legs of the machine, on which the bed 2 thereof rests.

B indicates one of the upright parts of the frame of the machine above the bed thereof, and *3* a transverse part of the frame extending between the upper ends of the said upright parts *B*. A driving-shaft on which is a balance-wheel, *4*, has a geared connection, as shown, with a crank-shaft, *5*, which has a pitman-connection with a platen, *6*, as shown, whereby said platen is given a vertically-reciprocating motion over the bed 2. A table, *7*, ordinarily of suitable wooden construction, is attached to one side of the bed 2, as shown in Figs. 1 and 2, whose upper side is in the same plane as the bed 2.

In the employment of machines of this class for cutting envelope-blanks from a pile of

paper by forcing a cutter of the proper form 55 through said pile of paper, a cutter-board, *8*, is used of a considerable superficial area and of a thickness of three to four inches, which is made from hard, and consequently heavy, wood, and is provided on one end with a handle, *9*, and on the opposite end with a metallic strip, *10*, which serves, more or less, to maintain the cutter-board in proper form and support it under the action of the above-described cutter when the latter is forced against its 65 surface. The said cutter-board is of such considerable weight in itself, and especially when a thick pile of paper is laid thereon from which said blanks are to be cut, that when said cutter-board is allowed to rest with 70 the whole of its under surface in contact with the bed and the table of the machine the sliding movement which is required to push the cutter-board and its load of paper under the platen 6 demands such an expenditure of 75 strength by the operator as makes it very fatiguing and prevents the work from being done expeditiously.

To obviate the above-referred-to inconvenience and provide supporting devices for the 80 cutter-board and the paper thereon, whereby said board is temporarily supported above the plane of the bed and table of the machine while the bed is being moved to and fro between the bed and the platen of the machine, 85 rollers 12 are supported on suitable bearings within the bed 2 of the machine, whose peripheries normally project slightly above the plane of the bed, as shown in Figs. 1 and 3, and similar rollers, 13, are hung in the table 7 of 90 the machine, on which the cutter-board moves and is supported. The said rollers 12, however, which are hung to rotate in the bed of the machine, are made capable of supporting the weight of the cutter-board and paper and the cutter which is used while the latter-named parts are moved under the platen; but the bearings of said rollers are movable vertically, so that said rollers shall recede, leaving the cutter-board to bear directly against the upper side of the bed 2, when said platen moves downward against the cutter *C* and forces the latter through the pile of paper and against the cutter-board, and when the platen rises said rollers follow its vertical movement and lift the cutter-board above the plane of the bed and support it while it is drawn off from the latter, and thereby its movemen

is made comparatively free from any frictional resistance, since it moves on said rollers. The said rollers 12, which bear the weight of the cutter-board and the paper and cutter placed thereupon, have the journals thereof supported in boxes or bearings 14, whose lower ends are made of cylindrical form and fit into the upper ends of hollow cylinders 15, which are supported in a vertical position on a cross-bar, 16, secured to the under side of the bed, as shown in Fig. 1. The lower ends of said bearings 14 are somewhat reduced in diameter, as shown in Fig. 3, whereby a shoulder is formed thereon, against which the upper end of a spring, 17, bears, and the lower end of said spring, as illustrated in Fig. 3, bears on the upper enlarged end of a screw-bolt, 18, having a screw engagement with said cross-bar 16. The said springs 17, which sustain the weight of each roller 12 and a portion of that of the cutter-board and the things supported thereby, are made of suitable resistance to sustain the weight of said board, paper, and cutter, and they permit the above-referred-to receding motion of the rollers when the platen 6 is forced against the cutter C, and they lift the rollers and the cutter-board when the platen moves upward, so that said board rests only on the rollers. If the machine is to be used in cutting blanks from a thickness of sheets of paper, 19, of substantially uniform weight, said springs 17 may rest by their lower ends directly against said cross-bar 16; but since the weight of paper which is placed on the cutter-board is variable, and without some means of adjusting said springs, whereby they are made capable of a variable resistance, they would not at all times properly support and lift the cutter-board away from the bed of the machine, therefore the said screw-bolts 18 are provided, in order that said springs may be compressed or released, more or less, according to the weight which they have to sustain.

In cutting blanks for envelopes or other similar articles from a pile of sheets of paper, as above described, a mass of paper-cuttings is produced, which falls more or less off from the cutter-board onto the bed of the machine, and if not removed they constitute an obstruction, by dropping into the roller-openings in said bed, to the free rotary movement of the rollers when the cutter-board is moved over the bed, as described, and with the purpose of avoiding said inconvenience means are provided for brushing said cuttings off from the bed of the machine when the cutter-board is moved to and fro thereon, consisting of a brush or a piece of felt, x, which is secured in a pending position on one end of the cutter-board, as shown in Fig. 1, said brush or felt extending across one end of said board and having the lower edge thereof in contact with the surface of the bed when the cutter-board rests upon its carrying-rollers, as described, and thereby said felt or brush permits the cutter-board to move toward and

from the bed of the machine, as above described, without deranging said brushing device.

The above-referred-to rollers 13 in the table 7 of the machine rotate in fixed bearings, as their function is only to support the cutter-board while the paper 19 and the cutter C are placed thereon and while the board is moved from the table onto the bed of the machine, as above described. The said cutter-board-supporting rollers may consist of one or more, each being of sufficient length to constitute a suitable support for the cutter-board, two or four being preferable. Fig. 2 shows in full and in dotted lines four rollers, the latter arrangement being advantageous when a very large cutter-board is required.

What I claim as my invention is—

1. In a paper-cutting machine, the combination, with the bed provided with vertically-movable journal-bearings, of rollers supported in said bearings, the cutter-board resting and movable on said rolls, the reciprocating platen, and a cutter, substantially as and for the purpose described.

2. In a paper-cutting machine, the combination, with the bed provided with vertically-movable journal-bearings and sustaining-springs therefor, of rollers supported in said bearings, the cutter-board resting and movable on said rolls, the reciprocating platen, and a cutter, substantially as and for the purpose described.

3. In a paper-cutting machine, the combination, with the bed provided with vertically-movable journal-bearings, sustaining-springs therefor, and vertically-adjustable bearings for the lower ends of said springs, of rollers supported in said bearings, the cutter-board resting and movable on said rolls, the reciprocating platen, and a cutter, substantially as and for the purpose described.

4. In combination, the bed 2 of a paper-cutting-machine, one or more cutter-board-sustaining rollers hung to rotate in said bed, whose peripheries project normally above the plane thereof, a cutter-board capable of a reciprocating horizontal movement on said rollers, and a brushing device, substantially as described, attached to one end of said board, having one end thereof in contact with the surface of said bed, substantially as set forth.

5. In combination with the bed of a paper-cutting machine, a cutter-board-sustaining roller, substantially as described, hung to rotate in said bed, the cylinders 15, supported vertically under said bed, the roller journal-bearings 14, having their lower ends entering said cylinders, the springs 17, constituting yielding supports for said bearings, and the screw-bolts 18, sustaining said springs, substantially as set forth.
